BUILDING CONSTRUCTION

John James O'Reilly, Woodside,
Long Island, N. Y.

Application May 26, 1931, Serial No. 540,111

17 Claims.

(Cl. 72—1)

This invention relates to improved structures and structural elements and methods and has for its primary object to provide greater flexibility with complete structural safety in the design and 5 construction of buildings and other structures through the use of the materials and methods hereinafter described.

It is a more particular object of my invention to provide a method whereby structures may be 10 assembled from factory finished units with greater speed, safety and economy than has ever been possible heretofore with other materials and methods.

My invention also contemplates providing 15 nearly perfect insulation against heat and cold in the factory finished units while maintaining their nearly universal architectural and structural characteristics and without impairing their value from a standpoint of safety and/or economy.

A still further object of my invention is to provide homes and other buildings which will not burn, rot, corrode, crack or become infested with vermin, and which while virtually immune 20 to earthquake or tornado may yet be readily transported from place to place and set on any sort of foundation or floated on water.

With the above and other objects in view the invention consists in the structures and structural materials and methods and other features 30 hereinafter described, shown or disclosed, and in the form, assembly, construction and relative arrangements newly disclosed and in the processes involved, and in the relative arrangement and 35 construction of the several parts, as will be hereinafter more fully described, illustrated in the accompanying drawings, and subsequently incorporated in the subjoined claims.

In the drawings in which I have shown several 40 practical embodiments of my invention:

Figure 1 is a sketch in plan showing a plurality of metal plates placed in spaced relation face downward for the purpose of welding same together from the back.

Figure 2 is a sketch in plan showing the intermediate framing which is designed to hold 45 the outer and inner sheathing together.

Figure 3 is a fragmentary section in plan taken through the assembled sheathing and frame 50 near the lower left hand corner of same.

Figure 4 is a section in plan taken through two units of the outer walls of the house (Figure 9) where they come together to form the left hand rear corner of same. The view is fragmentary.

Figure 5 is a section in plan taken through

fragments of two assembled wall units where they come together to form the right hand front corner of the house (Figure 9). A section in elevation through fragments of the left hand wall and the second floor would be similar, providing, that 5 it is understood that the wall section (x9) would not stop at the second floor level, but would continue on to the roof, and that the facings might differ.

Figure 6 is a section in plan taken through 10 two fragments of wall units showing how they might be brought together in mitred arrangement at the corner of the house. This is an embodiment of Figure 4.

Figure 7 is a section in plan taken through two 15 fragments of wall sections, or two fragments of partition sections, showing how they might be brought together butt to butt fashion in a structure different from that shown in Figure 9.

Figure 8 is a section in elevation taken through 20 a fragment of the floor section x10 and a fragment of the partition section x12. It shows the fastening of a partition section to the ceiling and inverted it would show the fastening of a partition unit to the floor.

Figure 9 is a diagrammatic sketch of the factory finished units assembled together to form 25 a house. The front facade section has been omitted from this view and the interior has been rendered partly in perspective.

Figure 10 is a section in elevation taken through 30 a fragment of the factory finished roof unit x4 Figure 9.

Figure 11 is a fragmentary sketch section taken 35 in elevation through an embodiment of the floor and partition construction disclosed in Figure 9.

Figure 12 is a fragmentary section in plan taken through the jamb of window o10. A section through the head or sill would be very similar differing possibly in the matter of trim.

Referring in more detail to the drawings (Figure 1) the symbol *a* refers to any individual plate in the group. These plates are preferably steel or steel alloy but other materials may be used. The six plates shown in the view are arranged to form the outer sheathing for the front facade of a small home. The symbol *o1* refers to a window opening, *o2* refers to a door opening. The symbol *a1* refers to the edges of the metal plates which are turned up around the openings and around the outer edges of the sheathing. The sheets are to be arc welded to each other continuously along the seams indicated by *s* in the view to obtain a single piece of sheathing which may be readily factory finished on its face with a view

5

55

to completely hiding the welded seams. Six other sheets are assembled in a similar manner to form the inner sheathing for the front facade of the house shown in Figure 9.

- 5 Figure 2 is a sketch in plan showing the intermediate framing which is designed to hold the outer and inner sheathing together. This entire frame as indicated in view is formed by arc welding metal plates together. Further details for 10 the making of these frames may be found in pending patent application Serial #331,308 filed January 9th, 1929. The symbol *b4* indicates a wall stud made from a metal plate and each one of these wall studs is arc welded to the header or 15 cross framing member at each end of the studs indicated by the symbol *b2* in the sketch. The symbol *b5* indicates a shorter header or cross framing member used for framing out at the head and sill of the openings *o1* and *o2*.
- 20 In Figure 3 the symbol *CW* indicates the arc welding of the bent parts of the sheathing *a1* to the stud *b4*. These bent parts are similarly welded to the cross header *b2* at the top and bottom of each opening and to the studs *b4* at both 25 sides of the openings. The general view of the fastening of the bent parts *a1* to the cross header *b2* at the top and bottom of the facade would be very similar except for the different arrangement of the intermediary members *b2* and *b4*.
- 30 When all of this welding has been completed the unit is tested and made airtight. The symbol *SW* is used to indicate that the inner and outer sheathing is spot welded to the intermediary framing. This spot welding may be either continuous or intermittent along the studs and on both sides of same.
- The symbol *P* indicates the finish applied to the metal plates under ideal conditions in the factory. This finishing coat which is preferably 40 of the baked-on enamel type is now in common use on many types of metal products. It covers and to a great extent hides the hidden joint *HJ* and the arc welding deposits *W* in back of what were formerly seams *s* in Figure 1.
- 45 Figure 4 the symbol *f1* indicates finishing materials of a monolithic stucco type applied directly to the metal plates *a* which have been roughened for the purpose of providing a good clinching surface. The view also shows the method used 50 for fastening two wall units where they come together at the corner of the house, or the method used for fastening the roof to the top of the wall, or if inverted it would show the method for fastening the first floor to the bottom of the wall, 55 but in order to visualize the latter two arrangements it would be necessary to first consider the view as a fragmentary section taken through the wall section *x9* and the roof section *x4* or the wall section *x9* and the first floor section *x6*. It 60 should be noted that the floor and roof sections may project beyond the outer face of the wall sections or finish flush with same. It will also be noted that any predetermined part or parts of the plates *a* or the bent portions of same *a1* may 65 be left exposed or free of finishing materials. This is for the purpose of providing a ready means for field welding of the various factory finished sections which form the house (Figure 9) or any other type of building. This field welding 70 is preferably electric arc welding and is accomplished by inserting an arc welding electrode into the open joints *JW* touching same to the metal parts of the sections and the leveling screeds *73* and withdrawing same slightly to form an arc 75 which deposits molten metals as indicated at *JW*.

These welding deposits are kept back of the face of the units to facilitate finishing off these joints with suitable materials and hiding the welding deposits. Metal leveling screeds *73* are used in between the units as shown, and the units are welded to each other and to the metal leveling screeds. The method of arc welding through an open joint has been described more fully in pending patent application Serial #322,285 filed November 27th, 1928, and elsewhere.

5 Figure 5 shows the method of field fastening and the use of a cornice moulding *m* at the intersection of a wall (or partition) and ceiling units. The two units shown in this view are factory finished outside *f2* with wire laths welded to the plates *a* and stucco of the monolithic type, that is poured on in one coat instead of being plastered on in several coats. On the inside the finish is the same as described for Figure 3. The cornice moulding *m* has been arc welded to the inner plate *a* through the welding hole *H4*. This method of welding through a small hole has been described in more detail in pending patent application Serial #331,308 filed January 9th, 1929.

10 In Figure 6 the symbol *f3* indicates a factory 20 finish applied to the plates *a* which have aggregates indicated by the symbol *G* partly embedded in the metal plates and partly exposed to provide a good clinching surface. This type of 25 finish has been explained in more detail in Letters Patent #1,807,323 issued May 26th, 1931.

30 In Figure 7 the symbol *aa* indicates that the metal sheets have a polished surface and do not require additional finishing materials as they are highly rust resistant. They have been welded together as shown at *JW* and the welding deposits have been brought out beyond the face of the units and then machined or ground off flush, as shown, with the outer surfaces of the polished metal plates *aa*. It should be noted that the sections shown in Figure 7 are made from two 35 sheets of metal one back and one front and an intermediate frame and that there is no seam welding such as *s* Figure 1. A plurality of these 40 smaller sections would be welded together as 45 shown in Figure 7 to form a facade such as *x9*.

In Figure 8 the fastening is again indicated by the welding deposits *JW* connecting the two sections back and front and the leveling screeds *73*. The sections have factory finishes *f1*, *f2* and *f3*. The various finishes in the views are shown with a view to giving some of the numerous finishes which may be applied to the plates. Others 50 would naturally occur to anyone familiar with the art, also, combinations of those shown or indicated herein.

The symbol *R4* Figure 8 indicates a reinforcing member around the opening *o7* in the partition stud *b2*. This hole or opening is cut in the neutral axis of the stud and is used for exhausting the 55 air from the interior of the section.

In Figure 9 the interior has been rendered partly perspective to indicate more clearly the arrangements, disposition, openings, etc. Each unit forms a complete wall *x9* or a complete floor *x10* or *x6* or a complete partition *x12* or a complete roof *x4*. While not shown in perspective the one roof section *x4* covers the entire roof projecting slightly beyond the outer face of the wall all around to shed rain without dripping on the wall. The symbol *o30* indicates a door and frame in the partition unit *x12*. The symbol *o4* indicates a stairwell opening in the floor unit *x10*. The symbol *o10* indicates a window and frame in the wall unit *x9*. All openings are trimmed com-

pletely at the factory and include either glazed windows or doors wherever they occur. The concealed piping necessary to the building is built into the sections or units in the factory and connected in the field in the general manner described in pending patent application Serial #331,308 filed January 9th, 1929.

In Figure 10 the metal plate *a* on the under-side of the roof section is kept free of finishing materials as shown at CO to provide a ready means for welding the roof section to the wall section. The construction in this view is slightly different from that disclosed in Figure 3. Alternate joists *b10* are welded to the upper sheathing. Lower alternate joists *b10* are welded to the lower sheathing. This welding is preferably arc welding. The two layers of metal sheathing are completely insulated from each other except at the ends and sides where *b4* is welded to the top and bottom sheathing. Certain other joists may be welded to the top and bottom sheathing where the construction warrants same but the heat loss will be greater. This type of construction is very practicable for the outer walls, roof and ground floor.

In Figure 11 the partition sections or units *x12* are carried through continuously from ground floor to roof and the floor sections *x10* are welded to the wall and partition sections. This construction is especially valuable for a structure more than two stories in height having typical floor layouts.

The sections shown in Figure 9 may be varied to produce a structure of any size by anyone who familiarizes himself with the art. In a tall building on a relatively narrow base the partitions may be supported in tension from the roof, or the entire structure may be designed with a view to reciprocal support as described in pending patent application #408,265 filed November 19th, 1929.

In Figure 12 the symbol *m3* indicates an inner or outer trim welded to the plate *a* through the welding hole *H4*. The symbol *L* indicates three separate lights of glass with the insulating muntins *m4* separating them. These insulating muntins add to the insulating value of the structure by preventing the air from circulating between the lights of glass for any great distance.

Similar symbols refer to similar parts throughout the drawings.

The foregoing and the drawings largely explain the invention which is primarily a method of erecting or fabricating a plurality of factory finished metal sections and then assembling the said sections into a structure. This idea has been partly proposed previously, in Letters Patent #1,807,323 issued May 26th, 1931 to the present applicant.

Figures 1, 2 and 3 show the construction of a wall unit. Figure 10 shows the construction of a roof unit. The floor and partition units are made in a similar manner, excepting that intermediate floors such as the second floor in Figure 9 may or may not be insulated as will be explained herein-after. The units of course differ somewhat in shape, size, number of plates in sheathing, size, strength and number and disposition of supporting members, thickness, number and arrangement of openings, finishes, types of insulation, and in other details but all are constructed in virtually the same manner and as described.

In making a unit individual plates are provided and laid on a platform face downward to equal the size of the unit desired. The edges of these individual plates *a* are bent upward where

they form an outer edge of the unit and around the interior openings. They are welded continuously along the seams *s* to make them airtight and form one side of the sheathing for the unit. Another similar side of sheathing is made in the same manner for the opposite face of the unit. The turned up edges are less than half the thickness of the unit. The two sides are then placed around a frame of interior supporting members, such as shown in Figure 2, and welded thereto as previously described. The air may be pumped from the interior of the unit unless it has been filled with insulating materials, or if so desired the unit may not be insulated excepting by the natural air space in the interior. If the air has been pumped from the interior of the unit it should have been previously tested to make certain that it is airtight. This may be done by immersing it in water, pumping air into the interior with an ordinary service station air hose, and watching for air bubbles in the water.

When the insulating is satisfactory the plates may be pressed against the sides of the studs and spot welded thereto. Necessary finishes are then applied to the outer exposed surfaces. If there are door or window openings in the unit these are completely factory finished with sash, doors, glass, trim, hardware, etc., before the outer surfaces are finished in order that these parts may be finished at the same time as the rest of the unit. Doors are hung and hardware applied to same in the current manner with which all builders are fully acquainted. The application of the various finishes shown and indicated as *P*, *f1* and *f2* require no further explanation for those familiar with the arts involved. The finish *f3* is fully explained in the patent referred to. However, it should be noted that when the finish *f3* is used or the polished plates *aa* that the interior frame of supporting members is arc welded to the back of the sheathing plates *a* or *aa* as spot welding is not suitable. This is accomplished by welding the back of one sheathing to the frame, and then welding the other sheathing at the bent portions *a1* of the first sheathing, and relying upon the partial vacuum in the interior to keep the unfastened sheathing from vibrating.

When the units are constructed as shown in Figure 10 the frame of supporting members (Figure 2) may not be used. Alternate joists *b10* could be arc welded to the back of the lower sheathing and the other joists *b12* could be arc welded to the back of the upper sheathing. To the back of either layer of sheathing could be welded both end joists *b4* and both cross framing members *b2*, and the other layer of sheathing could then be applied and welded in the manner explained previously to joists *b4* and the cross framing members *b2* at the bent portions only. The joists *b12* may be deeper and thicker than the joists *b10* if there is any economy to be obtained. This would depend to a great extent to the load or burden in each individual case. The main idea of this type of framing is to insulate the two layers of sheathing as much as possible and prevent the loss of heat across the joists such as would occur in the construction shown in Figure 3.

The best results may be obtained with finishes such as *P f1* and *f2*, and it will be understood that these are the types of finishes I prefer to use with the construction shown in Figure 10. However, construction, insulation or type of finish would each take precedence under different circum-

stances, and for this reason some of the various embodiments are shown.

- The stair construction I prefer to use has been previously disclosed in pending patent application Serial #331,308, filed January 9th, 1929, and that application also discloses a type of floor which may be used to advantage. Same being a wood parquet backed with metal for welding to the plates of the floor construction which could be left exposed or free from finishing materials for this purpose. This same pending application shows the method used for welding trim and wood backed with metal flooring through a welding hole.
- 15 Customary floorings or floor coverings may be applied in the traditional manner.

The exterior wall and roof surfaces and the interior wall and ceiling surfaces may be provided with shop applied finishes of nearly universal scope. The present application does not pretend to explain all of the different combinations possible as they would naturally occur to anyone familiar with the art. It should be borne in mind that the finish indicated by the symbol 25 *f1* is poured on a surface, which has been previously roughened, in one coat, or it may be projected with a cement gun.

All of the exterior units should be insulated as thoroughly as possible. For this reason I prefer 30 the structurally insulating frame shown in Figure 10 for all exterior units. I also prefer to exhaust some air from the interior of these units, or else to fill the interior of same with granulated cork, or place therein other materials suitable 35 for insulating purposes.

The method used for obtaining a vacuum is virtually the reverse of filling a pneumatic tire. When the air is to be exhausted from the interior of a unit the hole *o1* Figure 8 would be 40 provided in each interior supporting member and in one outside supporting member. The air is pumped out very slowly through this one small outer hole through a vacuum pump line having a male thread engaging a female thread cut in 45 the hole. When the air has been pumped out sufficiently the pump line is removed and a screw quickly inserted in the hole and welded airtight. Because of the size of the hole compared to the 50 size of the unit and its interior capacity check valving, etc., is not necessary. It should be remembered that when the air has been pumped from the interior of a unit that the sheathing of plates *a* will have a tendency to buckle inwardly. They should, therefore, be properly designed to 55 resist this pressure in connection with the proper spacing of the interior supports *b4* or by lateral bracing such as *b5* between the joists, or by a combination of all three. Any final unevenness in the plates *a* would present a serious difficulty 60 unless it could be hidden by a heavy layer of facing materials. The construction shown in Figure 3 is suitable for interior units even without insulation. Insulated it would have certain advantages for exterior wall units on very high 65 structures, or for wide trussed roofs and in some cases might be structurally advisable for the construction of a ground floor.

It will be understood that the finish indicated by symbol *f3* in the present application generally 70 shows all of the aggregates symbol *G* concealed. However, some or all of these aggregates may be arranged to form a pattern or bond and left exposed by omitting the outer cementitious materials *cm* Figures 6 and 8.

75 The windows are assembled in the unit as fol-

lows: Outer trim, first then loosely, the outer glass, first muntin frame, middle glass, second muntin frame, inner glass, then the inner trim is applied, and the outer and inner lights of glass are wedged tight and puttied in the usual way. b

The house shown (Figure 9) may be arranged for artificial ventilation, or ventilating double hung windows or ventilating doors may be installed. The house may be arranged for gas or electric heating or outside heating service to 10 eliminate the cost of an ordinary heating plant with cellar, chimney, etc. However, nothing new is proposed herein either in ventilating equipment or heating apparatus as the stuff now on the market is thought to be suitable and its installation is thoroughly understood.

The roughing of the metal plates for finish *f1* is accomplished by criss crossing lines of arc weld deposits across their outer surfaces. The cutting of the openings in the sheets *a* and the 20 turning up of the edges *a1* is accomplished in the manner familiar to those acquainted with the art of sheet metal fabrication.

Soldering, brazing, etc., may be substituted for 25 welding in all or part of the work providing it is agreeable to the governing authorities.

The screeds *73* are merely long metal bars having a square or rectangular cross section preferably. They are used for perfect leveling and aligning of the units, and in some cases two or more might be necessary front or back or both for perfect shimming.

After the field welding has been completed the joint welding *JW* may be covered with suitable materials such as mortar, plaster, stucco, soft metal, etc., to provide a finish for the welding joints. The welding holes *H4* are similarly treated. The excess material projecting beyond the finished face of the units may then be ground off flush with same. This work may be done 40 either by hand or with a mechanical grinder.

The vertical and horizontal supporting members may be aligned as far as practicable in the field for the purpose of providing reciprocal support and for other purposes as explained in detail in pending patent application Serial #408,265 filed May 29, 1930.

It will be further understood that because of the universal scope of architectural, structural, legal and economic demands in building construction that much of the value of any material or method lies in its possibilities for universal application, but that it would be impractical to attempt to show more than a few embodiments 55 of the invention which I consider of the most importance in the present application. Other finishes, arrangements, combinations, etc., would obviously become apparent to anyone familiar with the art as they faced individual problems. Angles, T's, bars, Z's, channels, I beams, etc., 60 might be substituted for the plates *b2*, *b4*, etc., in the frame or materials other than metal might be substituted. Additional trim, knickknacks, etc., may be applied. The roof could be pitched 65 to any degree of slope or kept perfectly flat. Walls might follow the outline of a geometrical figure or curve. A structure of any size could be erected, or nearly universal application could be provided for the invention from the present 70 disclosure by anyone thoroughly acquainted with the art of building construction.

The structure illustrated in the drawings Figure 9 is designed for placing on the bare earth. Service connections such as water, gas, electricity, 75

sewers, etc., are to be made with flexible lead pipe in a ditch dug under the center of the structure. For other or larger structures any standard type of foundation could be used, preferably, the continuous type described in pending patent application Serial #408,265, filed November 19th, 1929, and indicated in fragmentary form in Figure 11 of the drawings filed with that application.

10 For the insulating muntins *m4* Figure 12 I prefer to use medium hard rubber. These muntins run vertically and horizontally and are fastened where they intersect to form a frame by means of notches in the manner commonly 15 used by sash makers. The lights of glass *L* Figure 12 are of standard manufacture.

It will be understood also, that the units *x6*, *x9*, 20 *x10*, *x12*, *x4* or some of them might be used in conjunction with other standard building materials in ways which would naturally suggest themselves to the mind of any experienced builder 25 facing a given situation in actual practice. The present application may be considered a continuation in part of U. S. Patent #1,807,323 and pending applications #322,285, #331,308 and #408,265 filed by the present applicant as noted hereinbefore.

From the foregoing it may be readily seen that anyone thoroughly familiar with building construction materials and methods could readily 30 construct a building from the units herein described. I have disclosed herein several practical embodiments of the invention which I consider of the most importance. Nevertheless, because of 35 the wide scope of architectural, structural, legal and economic requirements in building construction, it must be clearly understood that the invention may also be exemplified in numerous other alternative constructions, and I therefore 40 reserve all such legitimate changes as may be fairly embodied within the spirit and scope of the invention as claimed.

I claim:

1. In building construction the combination in 45 a major structural air-tight hollow metal part forming such as a complete wall of separate intermediary structural supporting members such as studs spaced precisely in close order array between two spaced layers of outer sheathing and welded thereto forming thus a plurality of separate compartments, with air exhausted for insulating purposes from the interior of each of the said compartments through re-inforced holes fashioned in the neutral axis of the said structural supporting members without material structural weakening of same, and an architectural finish on the exposed surfaces of the aforesaid 50 layers of outer sheathing concealing sufficiently for all practical purposes their welded seams also 55 any slight buckling in the said sheathing due to the lack of normal air pressure in the interiors of the aforesaid separate compartments with means for assembling the aforesaid major structural part with a plurality of other somewhat 60 similar parts in precise architectural and reciprocal structural relation and carefully concealed field welded continuity to provide such as a complete dwelling without damaging the said architectural finish.

70 2. A building unit comprising sheathings fastened together as an air-tight shell with an architectural concealment of such as seams, primary supporting members stiffening the sheathing on one main surface of the unit like- 75 wise secondary supporting members stiffening the

sheathing on the opposite main surface of the unit, a separation of the sheathing on the one main surface of the unit from the secondary supporting members likewise a separation of the sheathing on the opposite main surface of the unit from the primary supporting members, and means for assembling the unit readily and precisely in a structure. 5

3. A building unit comprising sheathings fastened together as an air-tight shell with architectural concealment of such as seams, internal plate members structurally stiffening the aforesaid shell longitudinally while braced laterally themselves by said shell, and means for assembling the unit readily and precisely in a structure. 10

4. A building unit comprising a precisely dimensioned shell, members structurally stiffening the aforesaid shell while laterally braced by same, an insulating separation of the two main surfaces of the shell throughout the main body 20 of the unit, and means for assembling the unit readily and precisely in a structure.

5. In construction the combination of a precisely dimensioned air-tight shell composed of a plurality of precisely spaced metal sheathings 25 fastened to each other by arc welding deposits, with an interior plurality of such as precisely spaced joists of flat shaped metal, longitudinal stiffening of the aforesaid shell by said joists with reciprocal bracing laterally of the joists by 30 the shell, and means for assembling the aforesaid shell and joists as a unit readily and precisely with other similar units to form such as a building structure.

6. In construction the combination of a precisely dimensioned air-tight shell composed of a plurality of precisely spaced metal sheathings welded to each other, with an interior plurality of such as spaced joists structurally stiffening one main surface of the aforesaid shell longitudinally, 40 another interior plurality of such as spaced rafters structurally stiffening the opposite main surface of the aforesaid shell longitudinally, also reciprocal bracing laterally of the aforesaid joists and rafters by the aforesaid shell, an insulating 45 separation of the one main surface and its joists from the opposite main surface and its rafters throughout the main part of the aforesaid shell, and means for assembling the shell and joists and rafters as a unit readily and precisely in a structure. 50

7. A building unit comprising a precisely dimensioned air-tight metal shell composed of a plurality of precisely spaced sheathings welded to each other, with an interior plurality of such as spaced plates structurally stiffening the ceiling surface of the aforesaid shell longitudinally, another interior plurality of such as spaced plates structurally stiffening the roof surface of the aforesaid shell longitudinally, also reciprocal 60 bracing laterally of its longitudinal stiffeners by said shell, an insulating separation of the ceiling surface and its stiffeners from the opposite roof surface and its stiffeners throughout the main body of the unit, and means for assembling the entire unit readily and precisely as a complete 65 ceiling and roof for such as a human dwelling place.

8. A building unit comprising two precisely dimensioned outer half shells each composed of a plurality of precisely spaced metal sheets and both fastened together in precise structural relation to each other as a precisely dimensioned structural shell, primary interior supporting members longitudinally stiffening one half shell 70 75

while reciprocally braced laterally themselves by same, secondary interior supporting members longitudinally stiffening the opposite half shell while reciprocally braced laterally themselves 5 by same, a structural separation of one half shell and its stiffeners from the opposite half shell and its stiffeners except at the sides and ends and other remote points of the building unit for insulating purposes by structural means, and 10 means for assembling the entire unit readily and precisely preferably as a complete roof for such as a dwelling place.

9. A structure composed of a plurality of precisely dimensioned metal shells composed each 15 of a plurality of precisely spaced metal sheets fastened together, spaced supporting members internally stiffening each of the aforesaid shells, joint spacing members between adjacent shells spacing them apart in precise structural relationship as the walls and the floors and the partitions and the roof of said structure, and fastenings such as welding deposits collectively 20 along the aforesaid joint spacing members and the adjacent parts of the aforesaid shells holding 25 them all together as a structure.

10. A structure composed of a plurality of precisely dimensioned air tight metal shells composed each of a plurality of precisely spaced metal sheets welded together, spaced supporting 30 members internally stiffening each of the aforesaid shells, joint spacing members between adjacent shells spacing same apart in precise structural relationship as the walls and the floors and the partitions and the roofs of said structure, and 35 such as welding deposits collectively along the aforesaid joint spacing members and the adjacent parts of the aforesaid shells holding them all together as a structure.

11. A mobile structure composed of a plurality 40 of precisely dimensioned metal shells each composed of a plurality of precisely spaced sheathings fastened to each other preferably by arc welding deposits, spaced supporting members internally stiffening each of the aforesaid shells, 45 joint spacing members between adjacent shells spacing them precisely in structural relation to each other, and fastenings such as arc welding deposits collectively along the adjacent parts of the aforesaid joint spacing members and shells 50 holding them all together as a structure.

12. A mobile structure composed of a plurality of precisely dimensioned air-tight metal shells each composed of a plurality of precisely spaced sheathings welded to each other, spaced supporting 55 members internally stiffening each of the aforesaid shells, reciprocal lateral bracing of each and every one of its plurality of stiffening members by each and every one of the aforesaid shells, joint spacing members between adjacent shells 60 spacing them precisely in structural relation to each other, and fastenings such as arc welding deposits collectively along the adjacent parts of the aforesaid shells and joint spacing members holding them all together as a structure.

13. A structure such as a dwelling place composed of a plurality of precisely dimensioned metal shells, a plurality of spaced metal plates internally stiffening longitudinally each and every one of the aforesaid shells and reciprocally

braced laterally themselves by same, a plurality of joint spacing members between adjacent shells spacing same precisely in their architectural and structural relationship, surfacing materials such as baked-on enamel on certain of the aforesaid metal shells, and fastenings such as arc welding deposits collectively along the adjacent parts of the aforesaid shells and joint spacing members holding them all together as a structure. 5

14. A structure composed of a plurality of preferably air-tight precisely dimensioned metal shells, a plurality of precisely spaced supporting members internally stiffening each one of the aforesaid shells, an insulating separation except at their sides and ends of the two opposite main 15 surfaces of at least one of the aforesaid shells, a plurality of joint spacing members between all adjacent shells spacing them apart in precise structural relationship, and fastenings such as welding deposits collectively along the aforesaid 20 joint spacing members and the adjacent parts of all of the aforesaid shells holding same all together as a structure.

15. A structure comprising a plurality of precisely dimensioned metal shells, a plurality of 25 spaced supporting members internally stiffening each one of the aforesaid shells, air exhausted from the interior of at least one of the aforesaid shells for insulating purposes in the structure, a plurality of joint spacing members between 30 all adjacent shells spacing same apart in their precise structural relationship to each other, and fastenings such as welding deposits collectively along the aforesaid joint spacing members and the adjacent parts of any and all shells holding 35 same all together as a structure.

16. A structure comprising a plurality of precisely dimensioned metal half shells each composed of a plurality of precisely spaced sheathings fastened to each other preferably by welding deposits, a plurality of spaced supporting members fastened to one side of each half shell and reciprocally braced laterally themselves by each such half shell, a structural assembly of all of the aforesaid half shells preferably in matched 40 pairs as the walls and the floors and the ceilings and the partitions and the roof of the aforesaid structure, a plurality of joint spacing members between adjacent half shells spacing same apart 45 in precise structural relationship, and fastenings such as arc welding deposits collectively along the aforesaid joint spacing members and the adjacent parts of the half shells holding same all 50 together as a structure.

17. A building frame comprising a welding band 55 for its sides and ends, a plurality of precisely spaced plate shaped supporting members fastened to the inside of said band each such supporting member welded flush with one face edge of the said band but held short of being flush 60 with the opposite face edge of same, an alternating arrangement of said spaced supporting members with regard to which face edge of the welding band they are held flush with, and means for laterally bracing the plate shaped supporting 65 members with sheathing and then welding the entire building frame and its sheathing as a unit in a structure.

JOHN JAMES O'REILLY.
